GLOVE

John M. Murray, New York, N. Y.

Application December 12, 1936, Serial No. 115,480

1 Claim. (Cl. 2—160)

This invention is directed to an improvement in gloves, and more specifically is directed to the provision of a glove the palm of which is equipped with a pocket for the reception of paper money, change, keys and similar small articles.

One of the objects of my invention is the provision of a pocket in the palm of the glove, the pocket opening and the closure therefor being so positioned that easy and ready access is had to the pocket with the hand held in natural position at the waist line, the natural curving of the fingers with the hand in such position eliminating the likelihood of the contents of the pocket falling out of the hand when the pocket is opened.

A further object of my invention is the provision of a glove the palm of which is equipped with a pocket, access to which is had through an opening extending transversely of the palm of the glove adjacent the base of the fingers, this positioning of the pocket opening together with the natural concavity of the hand and slight closing of the hand promoting opening of the pocket with ease and facility.

A still further object of my invention is the provision of a glove the palm of which is equipped with a pocket extending from the base of the fingers toward the wrist, the opening for the pocket being located adjacent the fingers, so that with the hand elevated, as in steering a motor car, for example, the contents of the pocket will naturally fall away from the mouth of the pocket toward the bottom thereof which lies in the palm of the hand of the wearer.

The pocket mouth in my improved construction is closed with some simple device such as interlocking fingers closed by a slide and known commercially under the name "Talon" or "Zipper", which are independent of the glove fastener, making it unnecessary to unfasten the glove in order to obtain access to the pocket.

In the accompanying drawing:

Fig. 1 is a view of the palm side of a glove constructed in accordance with my invention;

Fig. 2 is a similar view showing the pocket with the closure device in open position; and

Fig. 3 is a view on the line 3—3 of Fig. 2.

Referring to the drawing in detail, I designate a glove provided with the usual thumb and fingers 2 and 3, respectively, and with a fastener or other usual closure device 4.

Stitched or otherwise secured to the underside of the palm 5 of the glove is a piece of material 6, extending from adjacent the base of the fingers 3 toward the wrist 7.

The palm 5 is slit transversely, preferably en-

tirely across the glove from the forefinger to the little finger, as shown at 8, the material 6 extending just beyond this slit. The broken lines 9 indicate the edges or periphery of the material 6.

This construction, it will be apparent, provides a double walled palm for the glove, to form a pocket, access to which is had through the slit 8, at the base of the glove fingers.

The slit 8 is equipped with a closure member 10 which may take the form of engageable hooks 10 adapted to engage each other to hold the slit closed when the control slide 11 is moved in one direction, and to open the slit when the slide is moved in the opposite direction. Such fastening devices are commercially known as "Zipper" or "Talon" fasteners.

It will be seen from the foregoing that my invention provides a pocket glove possessing many meritorious features as compared with pocket gloves heretofore suggested. It will be apparent that by positioning the pocket opening or slit 8 at the base of the fingers, with the slit extending transversely of the glove, easy and natural access is had to the pocket, this feature too insuring that when the pocket is opened the contents of the pocket will not fall out of the hand.

Another advantageous feature of my improved glove will now be apparent, in that the pocket opening is so located with respect to the pocket and with respect to the palm of the glove that with the glove elevated as in steering a motor car, for example, the pocket extends downwardly, that is to say, the bottom of the pocket is below the opening so that the contents of the glove will be in the pocket in the palm of the hand.

What I claim is:—

A glove, a piece of material on the underside of the palm of the glove and extending transversely of the palm entirely across the base of the finger-receiving portion of the glove and rearwardly toward the wrist-receiving portion of the glove so as to underlie substantially the entire palm of the glove, the entire periphery of the material being stitched to the glove palm, the area of the material bounded by the stitching being greater than the corresponding portion of the glove palm to provide a pocket, a slit through the glove palm immediately adjacent the base of the finger-receiving portion of the glove to provide an opening for the pocket, and a slide fastener member for drawing and securing the edges of said slit together to close the pocket, said fastener being so disposed that the same must be moved transversely of the glove to open the slit.

JOHN M. MURRAY.
